INSECT CAGE

Allen S. Musikantow and Reuben G. Musikantow, both of
New Buffalo, Mich. 49117

Filed Jan. 3, 1967, Ser. No. 5,276

Term of patent 14 years

(Cl. D22—19)

FIG. 1

FIG. 2

FIG. 3

FIG. 4

FIGURE 1 is a perspective view of an insect cage showing our new design.

FIGURE 2 is a front view of said insect cage.

FIGURE 3 is a rear view of an insect cage.

FIGURE 4 is a top view of the said insect cage.

The side not shown is the same as the side shown in FIGURE 1.

The dominant features of my design reside in the portions shown in full lines.

We claim:

The ornamental design for an insect cage, substantially as shown and described.
